[57] CLAIM

The ornamental design for an evaporative cooler pump, as shown and described.

DESCRIPTION

FIG. 1 is a front perspective view of an evaporative cooler pump showing my new design;

FIG. 2 is a rear perspective view thereof;

FIG. 3 is a front perspective view of a second embodiment of an evaporative cooler pump showing my new design; and

FIG. 4 is a rear perspective view thereof.

The fragmentary showing of an electrical cord in all views is for ease of illustration and represents conventional wiring.
